WINDING MACHINE

Arthur F. Pym, Swampscott, Mass., assignor, by direct and mesne assignments, to Sibley-Pym Corporation, Lynn, Mass., a corporation of Massachusetts

Application December 30, 1929, Serial No. 417,305

15 Claims. (Cl. 242—3)

This invention relates to machines for winding elastic material such, for example, as the elastic thread used in manufacturing resilient cores for golf balls.

In winding spherical cores of elastic thread, the accurate control of the tension is an extremely important factor in producing a core of proper shape, balance and resiliency. The proper control of the tension is essential in starting the winding operation upon the small core center or kernel of rubber which is commonly employed at the center of the core. This is usually yielding in consistency and if the tension is permitted to increase above a predetermined degree, the kernel is elongated or made egg-shaped and the resulting core is non-symmetrical and poorly balanced. During the winding operation it is important to maintain the tension uniform, because uneven tension in the different winding zones tends to distort the core and also because the volume of thread supplied to the core varies in accordance with the tension to which it is subjected, that is to say, under high tension the cross sectional area of the thread is substantially reduced and more turns of thread must be supplied in producing a core of predetermined diameter. Finally, it is important to maintain the tension uniform in the outer windings of the core for the additional reason that otherwise a surface of con fused and uneven appearance is produced.

In one aspect my invention consists in novel mechanism for supplying an elastic thread continuously under a uniform degree of tension to a core or other body being wound. I am enabled to achieve the desired results by advancing the elastic cord to the winding mechanism at a predetermined uniform speed bearing a definite fractional ratio to the peripheral speed of the core being wound. An important feature of my invention consists in means for unwinding the elastic thread from the supply reel, constructed and arranged to maintain available a supply of unwound thread which is relieved substantially of all initial tension. It will be understood that where elastic thread is pulled directly from a supply reel, a variable tension results which is often very considerable as, for example, when the thread is being unwound from either end of the reel where it may become jammed to some extent against one head of the reel. In order to eliminate such initial tension, I contemplate the provision of driven means for rotating the supply reel at a uniform rate and for leading the unwound thread away from the reel so that it may be then handled in a uniform untensioned condition.

Another important feature of my invention consists in mechanism for engaging an elastic thread and advancing it or releasing it to the core being wound at a rate of linear speed bear-

ing a fractional ratio to the circumferential or peripheral rate of speed of the core. For example, if the feeding mechanism is operated to advance the elastic thread at one-sixth the rate of the circumferential rate of speed of the core, each unit length of the thread is stretched to six times its untensioned length and is tensioned a definite amount corresponding to such elongation. As herein shown, the core is rotated by peripheral engagement with a driven roller so that the peripheral speed of the core is uniform regardless of its diameter. The elastic thread is advanced to the winding point by a roller driven in definite speed ratio to the core-rotating roller preferably, and as herein shown, from a common source of power.

In another aspect my invention consists in improvements in core winding mechanism of the general type disclosed in the pending application of Charles R. Sibley, Serial No. 404,299, filed November 21, 1929, now Patent 1,982,933, issued Dec. 4, 1934. As in that machine, I propose to support and rotate the core by suitable rolls and to provide means for automatically detecting a zone of oversize diameter and keeping the core spherical by turning it to shift such zone out of the winding plane, but whereas the detecting means of that machine comprises a sphere mounted for universal movement, I have discovered that satisfactory results may be attained by the use of a roller having a curved periphery which makes substantially point contact with the core being wound. This construction presents the advantages of simplicity of construction and efficacy in operation, and at the same time produces a core possessing the desirable characteristics required.

As herein shown, the turning or twisting of the core to shift its winding zone is facilitated by mounting one of the core-supporting rolls for free endwise movement in a direction at right angles to the winding plane. The employment of such a freely movable roll in combination with a member of any kind which reacts with the core to displace the winding zone is believed to be broadly new and constitutes an important feature of the invention.

These and other features of the invention will be best understood and appreciated from the following description of a preferred embodiment thereof, selected for purposes of illustration and shown in the accompanying drawings, in which

Fig. 1 is a view of the entire machine in side elevation;

Fig. 2 is a view in perspective of the winding mechanism;

Fig. 3 is a plan view showing the core in winding position upon its supporting rolls; and

Fig. 4 is a diagrammatic view of the tension mechanism.

- As herein shown, the winding unit, the tension unit and the motor for driving these units are bolted to a base plate 10. The winding mechanism is mounted in a frame having a base 12 and an upright portion 14 having a boss 15 projecting from its rear face, in which is mounted a horizontally disposed stationary shaft 16. At its outer end the shaft 16 carries a hand wheel 17 and a driving pulley 18 and these are arranged to be engaged to or disengaged from a pinion 22 through the medium of a clutch 20. The clutch is operated by a vertically disposed shifting lever 21, having a latch piece 23 pivotally connected to its upper end by which the lever 21 may be latched in clutch-engaging position when it is desired to operate the winding mechanism continuously. The clutch may be of any commercial type and it is unnecessary, therefore, to describe its details of construction.
- The core to be wound is supported by a pair of spaced rolls arranged to rotate about parallel horizontal axes. One roll 28 is secured to a shaft 26 journaled in the frame 14 and carrying at its rear end a pinion 24 arranged to mesh with the driven pinion 22. The roll 28 tapers inwardly from each end, as shown best in Fig. 3, tending to center the core symmetrically. The other roll 32 is journaled upon a stationary shaft 30 extending through the frame and secured by a nut 36. At its outer end the shaft 30 is shouldered and provided with a nut 34, between which and a boss 38 on the frame is a space longer than the roll 32, so that the latter may rotate freely and also move endwise within the limits determined by the boss and the nut 34. The shaft 26 and the roll 28 are driven in a counter clockwise direction, as seen in Fig. 2, so that the core supported between the two rolls is rotated in a clockwise direction and the idle roll 32 is turned by its contact with the core in the opposite direction.
- In the upper part of the frame 14 is formed a hub or boss having a vertical bore, in which is mounted a rod 42 having a forked member 46 at its lower end in which is journaled a roller 48. The roller 48 is in the form of a disk having a transversely curved or convex rim and its axis is disposed parallel to the shafts 26 and 30 and symmetrically above them. The rod 42 is freely movable in its bearings and provided with a weight 44 at its upper end, by the action of which the roller 48 is maintained at all times in yielding engagement with the core at the top of the winding zone. The elastic thread to be wound is supplied to the core in a winding zone which corresponds to the central vertical plane of the roller 48 and to the minimum diameter of the tapered roll 28. As the core is wound, therefore, the elastic thread tends to build up and form a zone of oversize diameter in the core. The roller 48 reacts with this oversize zone in the core and causes the latter to turn and displace the winding zone, and this turning of the core out of the plane of the winding zone is facilitated by the endwise movement permitted in the idle roll 32.
- Elastic thread is supplied to the winding mechanism from a reel 62 journaled upon a transverse shaft 64 mounted between vertical bracket arms 60, one of which is shown in Fig. 1. Beyond the supply reel 62 is a pair of standards 82 in which is journaled a transverse shaft 80. An inwardly extending arm 74 is mounted to swing freely upon the shaft 80 and carries a drum 70 which is arranged to run upon the body of the elastic thread wound upon the supply reel. The drum 70 is fast to a shaft 72 carried by the

arm 74 and having at its rear end a driving pulley 76. The shaft 80 at its rear end is fast to a driving pulley 84.

At the left end of the base plate, as seen in Fig. 1, is mounted a motor having a shaft 52 with driving pulleys thereon. One of these pulleys is belted through a cross belt 50 to the driving pulley 18 of the winding mechanism, and the other pulley is connected through an open belt 54 to the pulley 84 on the rear end of the shaft 80. The shaft 80 carries a small intermediate pulley which, in turn, is connected through a cross belt 78 to the pulley 76 on the drum shaft 72.

It will be noted that both the roll 28, which determines the peripheral speed of the core, and the drum 70 are driven from the shaft 52. Their relative speed is, therefore, fixed in definite ratio. Constructed in the proportions shown, the peripheral speed of the drum 70 is substantially one-sixth of the peripheral speed of the roll 28. The drum 70 rests upon the body of elastic thread wound upon the reel 62 and by its rotation in a clockwise direction rotates the reel in anti-clockwise direction so as to unwind the elastic thread from the bottom thereof. The thread leaving the reel 62 is conducted away from it toward the right as shown in Fig. 1, and about an idle pulley 68 journaled in the upper end of the bracket 66 secured to the base plate 10. From the pulley 68 the thread passes to the left and makes a complete turn about the drum 70 from which it passes to a guide roll 92 mounted in a bracket 90 adjacent to the winding mechanism. After passing beneath the guide roll 92, the thread passes over the contracted waist of the roll 28 and about the core being wound.

The purpose of leading the thread away from the supply roll 62 is to clear the thread from the rotating reel, prevent back winding and maintain a supply of untensioned thread. In passing about the drum 70, a feeding relation is established which is practically positive as the frictional engagement of the elastic thread about the entire circumference of the drum prevents the possibility of slippage. The drum 70, therefore, by its rotation advances the thread to the core at a definite rate of linear speed which, as already stated, may be one-sixth of the peripheral speed of rotation of the core. It will thus be seen that the elastic thread is first unwound from the supply reel and relieved of initial tension and then advanced to the winding point at a predetermined rate. If the ratio is one to six, each unit length of thread will be stretched to six times its untensioned length in passing from the feed drum 70 to the core being wound and will be, accordingly, tensioned to a definite degree which, for convenience, may be expressed in terms of elongation. This method of handling the thread is represented diagrammatically in Fig. 4, where a peripheral movement of $\frac{1}{2}$ " of the drum 70 is shown as corresponding to a peripheral movement of 3" in the feed roll 28.

It will be apparent that the condition above outlined exists throughout the winding of the core and during its increase in diameter, and that the peripheral speed of the core is uniform regardless of its diameter and equal to the peripheral speed of the tapered feed roll 28. Similarly, the peripheral speed of the supply reel 62 is uniform regardless of its diameter and equal to the peripheral speed of the drum 70 which, by its weight, follows the body of thread upon the reel as the latter decreases in diameter. The construction above disclosed, therefore, insures a

supply of elastic thread to the core being wound under a predetermined uniform degree of tension throughout the winding operation. It will be apparent, moreover, that the degree of tension 5 may be readily varied by changing the ratio of pulley diameters and elongation imposed upon the thread corresponding to any desired degree of tension, or the same result may be secured by substituting for the drum 72 another drum of 10 different diameter.

It will be apparent from the foregoing description that the machine herein disclosed will operate to supply elastic thread to the core being wound under a uniform predetermined tension.

15 The degree of tension is of the greatest practical importance in the production of a satisfactory core, for reasons already pointed out. In respect to the resilient characteristics of the core, it may be noted that before the machine of my invention was available, manufacturers have had no assurance in advance as to the grade of the cores being produced but have been obliged to subject them individually to a resiliency test. A core wound with high tension travels farthest in response to a severe blow and balls with such cores 20 are desired by players of professional skill, whereas a ball having a core wound with a medium tension is much more satisfactory for the average player. By suitably controlling the rate 25 at which the thread is released to the core in the machine of my invention, it is possible to produce cores wound with a high tension, a medium tension or a low tension, as desired by the requirements of the trade.

30 In securing the improved results rendered possible for the first time by the use of my invention, a very important factor is the elimination of an uncertain and variable initial tension in the elastic thread. It will be understood that when a reel 35 is rotated merely by the pull of the thread, the tension required varies, not only on account of local irregularities, such as the thread being jammed against one end of the reel, but that as the size of the reel is reduced the moment arm 40 of the effective pull is decreased so that an increased tension is required to turn the reel, and also as the size of the reel decreases it must be rotated at increasingly higher speed to supply 45 the same length of thread. All of these uncertain factors are eliminated in accordance with the construction of my invention by the provision of the drum 70, which acts to turn the reel 50 at a uniform rate regardless of its size and of the position of the thread thereon. The thread fed 55 from the reel 62 is removed therefrom and led through a predetermined path, wherein its initial tension may be controlled or reduced to a negligible quantity so that when it is again engaged by the feed drum 70 it arrives in a uniform 60 condition in regard to its tension. The amount of winding tension is thereupon determined by the relative speed of the drum 70 and the core 65 rotating roller 28. The guide roll 92 is mounted to rotate freely in anti-friction bearings and, consequently, has no appreciable effect upon the 70 tension of the thread passing beneath it. While I have shown the thread as making a complete turn about the feed drum 70, it will be understood that any arrangement which enables this roll or equivalent mechanism to control the rate of feed of the thread would be within the scope 75 of the invention.

Having thus described my invention, what I claim as new and desire to secure by Letters Patent of the United States of America is:

1. In a winding machine, means for rotating a core at a predetermined rate of peripheral speed, and means for feeding an elastic thread thereto at a rate of linear speed bearing a predetermined fractional ratio to the peripheral rate of speed of the core. 5

2. In a winding machine, means for rotating a core at a predetermined rate of peripheral speed, and means located at a distance 10 from the core for feeding an elastic thread thereto and having elements acting to advance the thread at a predetermined and slower rate of linear speed than the peripheral speed of the core.

15 3. In a winding machine, means for rotating a core at a uniform peripheral speed, and feeding mechanism for an elastic thread, including a driven roll for advancing thread to the core at a fixed rate of linear speed which is slower 20 than the peripheral speed of the core.

4. In a winding machine, means for rotating a core at a uniform peripheral speed regardless of its diameter, a supply reel of elastic thread, and driven feeding mechanism for delivering thread from said reel without substantial initial 25 tension and for thereafter releasing it to the core at a fixed rate of linear speed which is slower than the peripheral speed of the core.

5. In a winding machine, driven means for 30 rotating a core at a uniform peripheral speed, a supply reel of elastic thread, and a driven roller for turning the reel to unwind the thread upon it and for positively advancing the unwound thread to the core at a predetermined fractional rate of the speed at which the core is wound. 35

6. In a winding machine, mechanism for rotating a core at a uniform peripheral speed, a supply reel of elastic thread, means for unwinding thread from the reel to relieve the thread of initial tension including a feed roller for engaging 40 the unwound thread and advancing it uniformly at a fractional rate of the speed at which the core is wound, thereby maintaining a predetermined tension in the thread.

7. In a winding machine, mechanism for rotating a core for winding the same at a uniform peripheral rate of speed, a driven feed roller acting to receive elastic thread without substantial initial tension and being driven to release it to the core at a fractional rate of the speed at which 50 the core is being wound.

8. In a winding machine, a roller arranged to support and rotate a core at a substantially uniform peripheral rate of speed, a feed roller arranged to receive elastic thread, a driven supply 55 reel for delivering thread without initial tension, and common driving means for both rollers connected thereto for rotating the same at predetermined different speeds, whereby thread is released to the core at a different rate from that at which it is wound thereon.

9. In a winding machine, mechanism for rotating a core at a substantially uniform peripheral rate, a supply reel of elastic thread, a driven roller associated with said core rotating mechanism and acting to unwind thread from the reel at a substantially uniform rate, the unwound thread thereafter making a complete turn about said driven roller and being released thereby to the core at a different rate from that at which 70 the core is rotated.

10. In a winding machine, a roller acting to rotate a core at predetermined rate of peripheral speed, a supply reel of elastic thread, a movable arm adjacent thereto, a driven roller car- 75

- ried by the arm and arranged to run upon the body of the thread in the reel to unwind the same, means for guiding the unwound thread away from the reel and then back to and about said driven roller, and means for driving said rollers at different speeds to advance thread to the core under a predetermined degree of tension.
11. In a winding machine, a core rotating roller, means for driving the same at uniform speed, and mechanism for advancing an elastic thread thereto including a feed roller and means for driving it at a peripheral speed bearing a predetermined fractional ratio to the peripheral speed of said core-rotating roller.
10. 12. A winding machine comprising means for supporting and rotating a spherical core about a predetermined axis to receive an elastic thread and at the same time leaving the core free to be angularly displaced, means for delivering thread in a definite winding zone, and a roll with a convex rim, journaled to rotate about an axis extending at all times at right angles to the winding zone, contacting with the core in the winding zone and tending automatically by reacting with the wound thread to displace the core as the diameter of the winding zone increases.
13. A winding machine comprising means for rotating a spherical core about an axis at right angles to its winding plane to receive an elastic thread, and a roller with a transversely curved rim contacting with the core, the roller being confined to rotate with its rim in said plane and reacting with the most recently delivered turns of thread to displace the core to one side or other from the point of contact.
14. In a winding machine, means for rotating a core at a uniform rate of peripheral speed throughout the winding operation and about a predetermined axis to wind an elastic thread thereon, and means acting independently of the pull on the thread for releasing thread to the core at a rate of linear speed bearing a fractional ratio to the circumferential rate of speed of the core.
15. In a winding machine, means for rotating a core at a uniform rate of peripheral speed to wind an elastic thread thereon, a roll acting to engage and hold back thread running to the core, and means for driving the roll at a rate such that the thread is released to the core at a slower linear speed than that at which it is wound thereon.

ARTHUR F. PYM.
